UNITED STATES PATENT OFFICE.

ELEMIR J. NEY, OF LOWELL, MASSACHUSETTS, ASSIGNOR TO THE LOWELL MANUFACTURING COMPANY.

DESIGN FOR A CARPET-PATTERN.

Specification forming part of Design No. 1,541, dated February 25, 1862.

To all whom it may concern:

Be it known that I, ELEMIR J. NEY, of Lowell, in the county of Middlesex and State of Massachusetts, have originated and designed a new Pattern for Carpets or other Fabrics, of which the following is a full, clear, and exact description, reference being had to the accompanying drawings, making part of this specification.

Figure A is an octagonal block surrounded by a solid frame 1. Fig. B is similar to A and surrounded by a frame similar to 1. Fig. C is a smaller block also surrounded by a solid frame.

Corners 2 3 4 5 are fourths of blocks similar to C.

6 7 8 9 are halves of figures similar to Fig. C.

D is a group of flowers and leaves with branches or sprigs extending toward corner 5.

E is another group of flowers and leaves with sprigs extending toward corner 3. Portions of these groups respectively overlap the frame of Fig. 6 and the frames of Figs. A, B, C, 7, and 8.

The remaining figures in the design are small square blocks, which lie between the frames before mentioned.

The colors employed for the different portions of the design may be varied to suit the taste and wish of the manufacturer.

What I claim as my invention, and desire to secure by Letters Patent, is—

The design or pattern for carpets or other fabrics herein set forth.

E. J. NEY.
